(57) CLAIM

The ornamental design for a combination pillow and baby bottle holder, as shown and described.

DESCRIPTION

FIG. 1 is a perspective view of a combination pillow and baby bottle holder of my design, shown in an open condition.

FIG. 2 is a top view of the combination pillow and baby bottle holder of FIG. 1, in a closed condition.

FIG. 3 is a bottom view of the combination pillow and baby bottle holder of FIG. 2.

FIG. 4 is a view of the combination pillow and baby bottle holder in a closed condition, as from the right end of FIG. 1.

FIG. 5 is a view of the combination pillow and baby bottle holder in a closed condition, as from the left end of FIG. 1. FIG. 6 is a front view of the combination pillow and baby bottle holder of FIG. 1, in a closed condition; and, FIG. 7 is a back view of the combination pillow and baby bottle holder of FIG. 6.

The broken lines depicting baby bottles in FIGS. 1, 4 and 5 are for illustrative purposes only and do not form part of the claimed design. The broken lines shown on the pillow and on the strap that secures the baby bottles represent stitching.
